UNITED STATES PATENT OFFICE.

FRANK AHLBURG, OF LOS ANGELES, CALIFORNIA, ASSIGNOR TO ELECTRIC FRUIT MARKING CO., OF LOS ANGELES, CALIFORNIA, A CORPORATION OF CALIFORNIA.

MARKING MACHINE.

Application filed November 14, 1921. Serial No. 514,958.

To all whom it may concern:

Be it known that I, FRANK AHLBURG, a citizen of Germany, and a resident of Los Angeles, county of Los Angeles, and State of California, have invented a new and useful Marking Machine, of which the following is a specification.

My invention relates to means for marking articles especially nuts.

One of the objects of the invention is the provision of a machine for the rapid marking of walnuts. Other objects of the invention include the provision of improved means for mounting the marking dies, improved means for conveying the nuts to the dies and improved means for regulating the pressure of the dies.

My invention possesses other objects and features of advantage, some of which, with the foregoing, will be set forth in the following description of my invention. It is to be understood that I do not limit myself to the showing made by the said description, as I may adopt variant forms of my invention within the scope of the claims.

Referring to the drawings: Fig. 1 is a side elevation of the nut marking machine of my invention. Fig. 2 is a plan view of two units of my marking machine. Fig. 3 is a vertical sectional view, the plane of the section being indicated by the line 3-3 of Fig. 1. Figs. 4 and 5 are respectively, plan and side elevation of a link in the feed belt comprising part of my machine. Fig. 6 is a side elevation of the counter-balancing means for adjusting the pressure of the dies on the nut.

In general terms the marking machine of my invention comprises a conveyor for carrying the nuts to be marked under the marking means. The marking means comprises a succession of dies resiliently mounted on a flexible endless belt. Movement of the nut carrying conveyor brings each nut under the end of the flexible marking belt which gravitally rests upon the nut as it is being marked. Means are provided for rotating the marking belt at a faster speed than the carrier belt, which results in rolling the nut under the die. Means are also provided for varying the effective weight of the marking means so that the pressure of the dies on the nut may be regulated. Means are also provided for inking the dies

and for supplying a succession of nuts to the carrier belt.

More particularly my device comprises a frame 2 upon which the mechanism is mounted. Mounted on shafts 3 and 4 journaled in the frame are drums 6 and 7 respectively. These drums are formed with annular grooves arranged in pairs as shown in Fig. 3 and in each pair of grooves are arranged belts 8 preferably formed of rubber. The belts are rounded on the outer surface and vary at regular intervals in the size of the cross section so that the two belts of each pair have alined recesses which together provide pockets in which the nuts 9 to be marked may lie. In the drawings I have shown but two units of the marking machine but it will be obvious that the drums 6 and 7 may be made of any desired length so as to accommodate as many pairs of carrier belts as desired, each pair carrying a succession of nuts to the marking mechanism. Means are provided for feeding nuts to be marked upon the carrier belt.

Arranged on the shaft 11 journaled in the frame 2 and on the shaft 12 journaled at any convenient point, is mounted a conveyor for each pair of carrier belts 8. The conveyor is formed of links 13 illustrated in Figs. 4 and 5 and as shown each link comprises a pocket large enough for one nut to lodge in. The feed conveyor comprising the links 13 and the marking conveyor comprising the carrier belts 8 are driven in synchronism so that nuts from the pockets in the links 13 fall into the pockets of the marking conveyor. Synchronism is secured by fixing sprockets 14 of equal size on each of the shafts 4 and 11. A chain 16 encircles these sprockets and sprockets 17. The shaft 4 is rotated by connection with the motor 18 thru chain or belt 19.

Means are provided for filling the pockets of the feed conveyors with nuts. Arranged adjacent the outer end of the feed conveyors is a broad belt 21 upon which the nuts to be marked are dumped by hand. Interposed between the downward turn of this broad feed belt and the lower end of the feed conveyors are deflectors 22 alternated with short chutes 23. As the nuts are carried over the turn of the feed belt they necessarily fall into the chutes and are picked up by the first vacant pocket of the

feed conveyor. Should more than one nut fall into the same chute, the lower one is picked up, the next one falling into the pocket behind. Of course the quantity of 5 nuts placed on the feed belt 21 is controlled by the capacity of the feed conveyors.

Means are provided for marking the nuts while on the marking conveyor. Loosely mounted on the shaft 26 journaled in the 10 upper part of the frame are a number of frames 27 which are made adjustable in length by means of lapped ends secured by bolts 28. The mounting of the frame 27 upon the shaft 26 is effected by means of a 15 yoke 29 between the arms of which a pulley 31 is fixed to the shaft 26. The lower end of the frame 27 is also provided with a yoke 32 in which the pulley 33 is journaled on the shaft 34 fixed in the yoke. An adjustable stop is provided for limiting the downward movement of the outer end of the frame about the axis of the shaft 26, and comprises an arm 35 extending outwardly 20 under the projecting end of the shaft 34. 25 The arm 35 is pivotally mounted on the frame 2 and is provided with an adjusting arm 36 the position of which is controlled by the adjusting screw 37. There is a frame 27 mounted directly above each marking 30 conveyor or pair of carrier belts 8 and, as shown in Fig. 2, one stop arm 35 may be arranged between each two frames.

The lower pulley 33 is faced with a sponge 35 rubber rim 38, and a thin flexible belt 39, preferably of rubber, is disposed upon the pulleys 31 and 33 of each frame. Closely spaced on each belt 39 are the dies 41 for marking the nuts. The belt 39 is rotated in the same direction as the marking conveyor 8 and preferably at higher speed so that when the belt 39 engages the nuts on the marking conveyor, the nuts are rolled under two or more of the dies. Because 40 of the flexible nature of the marking die belt and because of the deformable nature 45 of the rim 38 over which the marking belt runs when the dies are in contact with the nuts, a complete contact of all portions of the die is secured on the face of the nut. 50 Since the nut is rolled between the die belt and the supporting belts 8, each nut will be marked by two or more of the dies, and no matter how uneven the surface of the nut may be there is bound to be at least 55 one clear impression. The shaft 26 is driven by a gear 42 mounted for rotation with the sprocket 17 and of such size as to give the desired ratio of speed.

Means are provided for varying the weight 60 or pressure exerted by the marking belt upon the nuts. Each yoke 29 is provided on one side with an extension on which is rotatably mounted a collar 43. A set screw 44 provides means for fixing the collar to 65 the yoke extension. Slidably mounted in

the collar 43 is a rod 46 carrying a counter-balancing weight 47 on its outer end. A set screw 48 provides means for fixing the position of the rod 46 in the collar. It will be observed that by varying the position of 70 the weight 47, by means of the two set screws 44 and 48, the pressure of the dies upon the nuts may be varied as conditions require. If the weight is in the position shown in Fig. 1 part of the weight of the 75 frame 27 and the pulleys and marking belt is counterbalanced and the unbalanced weight determines the pressure exerted upon the nuts. If the weight 47 were shifted to the opposite side, its weight would be added 80 to the weight of the frame and allied parts so that the pressure upon the nuts would be materially increased.

Because of the pivotal mounting of the marking belt, no grading of the nuts for 85 size is necessary before they are marked and the same pressure is exerted upon each nut irrespective of its size.

Means are provided for inking the dies. Arranged in the upper end of the frame 2, 90 adjacent the shaft 26, is a reservoir 51 for the marking ink in which a feed roller 52 is adapted to rotate. A transfer roller 53 is interposed between the feed roller and the dies and as the belt 39 moves, the dies are 95 brought into engagement with the feed roller which is rotated thereby and deposits ink thereon.

I claim:

1. In a marking machine, a conveyor for 100 the articles to be marked, a flexible belt gravitally engaging said articles, flexible dies on said belt, a pulley of resilient material for supporting said belt while engaged with said articles, and means for moving the belt in time with the conveyor.

2. In a marking machine, a conveyor for 110 the articles to be marked, a belt gravitally engaging said articles, dies on said belt, and means for moving the belt faster than the conveyor.

3. In a marking machine, a conveyor for 115 the articles to be marked, a belt gravitally engaging said articles, dies on said belt, means for moving the belt in time with the conveyor, and means for varying the pressure of said belt upon said articles.

4. In a marking machine, a belt gravitally 120 engaging the articles to be marked, dies on said belt, means for feeding said articles to said belt, and a pulley of resilient material for supporting said belt while engaged with said articles.

5. In a marking machine, a belt gravitally 125 engaging the articles to be marked, dies on said belt, means for feeding said articles to said belt and means for varying the pressure of said belt on said articles.

6. In a marking machine, a shaft, a pulley 130 on said shaft, a frame pivoted about said

shaft, a second pulley of resilient material arranged in said frame, a flexible belt about said pulleys, flexible dies on said belt; and means for feeding articles to be marked into engagement with said belt.

7. In a marking machine, a shaft, a pulley on said shaft, a frame pivoted about said shaft, a second pulley arranged on the outer end of said frame, a belt on said pulleys, dies on said belt, an arm on said frame, an adjustable counterweight on said arm for varying the gravitational thrust of said second pulley, and means for feeding articles to be marked into engagement with said belt under said second pulley.

8. In a marking machine, a pivotally mounted frame, pulleys on said frame, a

belt on said pulleys gravitally engaging the articles to be marked, dies on said belt, means for varying the gravitational thrust of said frame, belt and dies upon said articles, and means for feeding articles to be marked under said belt.

9. In a marking machine, a pivotally mounted frame, pulleys on said frame, a belt on said pulleys gravitally engaging the articles to be marked, dies on said belt, a conveyor having pockets therein for moving articles to be marked below said belt, and means for placing a succession of said articles in said pockets.

In testimony whereof, I have hereunto set my hand.

FRANK AHLBURG.
